(57) **CLAIM**

The ornamental design for a strap wrapping tool, as shown and described.

DESCRIPTION

FIG. 1 is a perspective view of a strap wrapping tool; FIG. 2 is a front view of the strap wrapping tool in FIG. 1; FIG. 3 is a back view of the strap wrapping tool in FIG. 1; FIG. 4 is a right side view of the strap wrapping tool in FIG. 1;

FIG. 5 is a left side view of the strap wrapping tool in FIG. 1;

FIG. 6 is a top view of the strap wrapping tool in FIG. 1; and, FIG. 7 is a bottom view of the strap wrapping tool in FIG. 1.

The uneven broken lines delineate the boundaries of the claimed design. The even broken lines illustrate portions of the strap wrapping tool that form no part of the claimed design.
